Patented Apr. 18, 1899.

A. G. JACOBS.
CLOCK WINDING INDICATOR.

(Application filed June 20, 1898.)

(No Model.)

UNITED STATES PATENT OFFICE.

AUGUSTUS G. JACOBS, OF JONESTOWN, MISSISSIPPI.

CLOCK WINDING-INDICATOR.

SPECIFICATION forming part of Letters Patent No. 623,158, dated April 18, 1899.

Application filed June 20, 1898. Serial No. 683,933. (No model.)

To all whom it may concern:

Be it known that I, AUGUSTUS G. JACOBS, residing at Jonestown, in the county of Coahoma and State of Mississippi, have invented 5 certain new and useful Improvements in Winding-Indicators for Clocks, of which the following is a specification, reference being had therein to the accompanying drawings.

This invention relates to winding-indicators 10 for clocks.

The object of the invention is to produce an indicator which can be readily attached to 15 clocks of ordinary construction and which will show a signaling device when the clock is nearly run down and may also have a muffler for the striking apparatus of the clock. The visible indicator or signal is preferably 20 a folding fan which may fold into small compass and can be spread with very small expense of power.

The improvement consists in certain constructions and combinations substantially as hereinafter described.

Figure 1 is a front elevation of a clock-front 25 partly broken away to show the general arrangement of the indicator in the position in which the indicator is inoperative. Fig. 2 is a similar view showing visible indicator and muffler operating on the bell, as when the 30 clock has nearly run down. Fig. 3 is a front elevation of the fan and its operating wheel or pulley and connections. Fig. 4 is a front elevation of the signal-operating mechanism and part of the frame and other portions of 35 a clock-movement. Fig. 5 is an edge view of the signal-motor attachment as applied to a clock-frame.

The attachments which I make for connection 40 to a common clock are the motor part, shown in Figs. 4 and 5, and the fan, connected to a wheel and axle, Fig. 3, the parts being connected by an operating-cord, as indicated in the other figures.

Most clock-cases, as 1, have a molding, as 45 2, at the top of the casing, behind which there is a recess not visible directly from the front of the clock. This permits the attachment of my fan-shaped indicator 3, which when folded down will generally be invisible from 50 the front of the clock, or if visible will appear merely as a fan lying on the top of the clock-case.

The narrower end of the folding fan 3 is attached to a tape 4, which partially surrounds and is attached to an axle 5, and one of the 55 fan-sticks 6 is attached to a base-piece 7, as by a cord 8. The axle 5 is supported on suitable standards or brackets 9 from the base, and the axle has a wheel or pulley 11 rigidly connected thereto. 60

The partial rotation of shaft 5 in the direction of the arrow, Fig. 3, will spread out the fan, as indicated in Fig. 2, and the release of said pulley will permit the fan to fall back into the position of Fig. 3 or a lower position 65 on base 7, either by the weight of the fan or by its tendency to close itself when made of such material that the fan tends to close, or by reason of a weight, as 13, attached to wheel 11, or any usual means for closing a 70 fan. The cord 8 prevents fan-stick 6 from rising much beyond a position about parallel with the base 7 and a little above the same.

The base 7 can be attached to the top of the 75 clock, as by screws, and a small hole through the top of the clock-case permits the passage of cord 14 to the interior of the clock behind the dial. Cord 14 is attached to the wheel or pulley 11, and a hole in the clock-case large enough to pass cord 14 is all the 80 cutting found necessary with most clocks in making my attachment.

The fan can be opened or spread and closed or folded very easily, and when spread presents a large surface, which may have words 85 or ornamental designs thereon. I am aware that signals have been used to show that clocks have nearly run down; but none of those with which I am familiar can be made to show so large a surface with so little expenditure of 90 power as my fan-signal.

The gearing or mechanism for operating the fan-signal I attach to the clock-movement frame. A convenient form of attachment is shown, wherein piece 20 is a metallic strip 95 about as wide as one of the bars of a common clock-frame, and said strip or piece 20 has an integral hook 21 near its end and at the side, so that said hook will extend behind the bar 16 of the frame. The piece 20 has a bracket 22 attached, and a one-tooth gear 23 is held by said bracket to the winding-post 24 of the clock, so as to rotate with said winding-post. All that 100 is needful to attach the gearing to a common

clock-frame is to hook the hook 21 about the clock-frame and apply the one-tooth gear to the winding-post. Of course attachment could be made to other forms of clock by slight changes. The whole mechanism might be applied to other forms of clock by slight mechanical changes or directly and permanently to the clock-frame; but I prefer to have the mechanism detachable.

10 To base-piece 20 I attach the gear-wheel 30, said gear having teeth with which the one-tooth gear 23 engages, either in winding the clock or as the winding-post moves. The gear 30 may be provided with a stop-tooth to 15 stop the clock when it shall have run down. The teeth on gear 30 are of such number as will about make a rotation of gear 30 while the clock is running down.

On the disk-face of wheel 30 I attach a disk 20 31, provided with a broken-face ring 32 or a projection from the body of the disk in form of a broken ring. The disk 31 has a curved slot 33 therein, and a set-screw 34 in this slot serves to adjust the disk 31 relatively to wheel 25 30, so that the break in ring 32 may be adjusted circumferentially on gear 30 to permit the device to be made operative at a little less than a rotation of gear 30, say about twenty-two, twenty-three, or twenty-four 30 hours in a one-day clock or at seven or seven and one-half days in an eight-day clock.

A bent lever 35 is supported on a pivot, as 36, which pivot is supported on a suitable bracket, as 37, connected to piece 20. An 35 arm 38 of this lever rests against the broken ring 32 as gear 30 rotates, taking disk 31 with it; but when the break in the ring moves opposite the end of this arm 38 the arm 38 swings through the break in the ring under the 40 impulse of weight 39, attached to long arm of lever 35. This depression of the weight 39 draws on cord 14 and spreads the fan at the top of the clock. At the same time an arm 40 of lever 35 is swung against the bell or 45 sounder 49 of the clock and the bell is muffled. The spread fan and muffled bell are indicated in Fig. 2. The upper end of arm 38 has a hooked end with its outer under surface inclined, as indicated in Fig. 5. The arm 38 is 50 slightly elastic.

When the indicator 3 is spread, the clock may run until it runs down, but the spread fan will show that winding should be attended to, and the muffled bell will indicate the same 55 fact.

The direction of movement of gear 30 in running down is shown by the arrow, Fig. 1. In winding the clock the gear 30 rotates in the direction indicated in Fig. 2. The screw 60 34 by such rotation engages the right-hand side of lever-arm 38 and swings said lever to the position of Figs. 1 and 4. The hooked end of lever 38 will ride over ring 32 in moving out, but will engage the outer side of said 65 ring and will be prevented from swinging in toward the center of the ring except through the break in the ring.

The weighted arm of lever 35 may be in itself enough to spread the fan without an additional weight. The winding of the clock 70 permits the folding of the fan and removes the muffle from the bell.

It must be understood that in many details of my mechanism modifications may be made without departing from the spirit of the invention. I believe the invention to be as broad as the claims herein.

What I claim is—

1. A fan indicator for clocks, consisting essentially of a folding fan, a shaft to which the fan is connected, so that the fan is spread by the partial rotation of the shaft in one direction, and allowed to close by the partial rotation in reverse direction, a supporting-base by which the fan and shaft may be attached 85 to a clock-case, and means for connecting the shaft to the clock-movement to be actuated thereby.

2. In combination with a clock-case, a fan-support connected to said case, a folding fan on said support, a shaft connected to the fan to spread the same and a pulley on said shaft, a cord connecting said pulley to the clock-movement, and means for closing the fan, all combined substantially as described.

3. In a clock winding-indicator, the base-piece 20 having means for attachment to the clock-movement frame, a single-tooth wheel supported on said base-piece and engaging the winding-post of the clock, a gear actuated by said single-tooth wheel and carrying a broken ring-bearing, and a lever having an arm in position to swing through the break in the said ring, said lever connected to and operating a visual signal, all combined substantially as described.

4. In a clock winding-indicator, the base-piece having means for attachment to the movement-frame, a gear-wheel carried by said base-piece and driven from the clock-movement, the broken ring carried by said gear, a lever suitably supported and having an arm in position to bear against said ring and to swing through the break thereof, and a muffle connected to said arm and in position to 110 muffle the striking apparatus of the clock when the lever moves through the break in the ring, all combined substantially as described.

5. In a clock winding-alarm, the combination with the clock-movement, of a visual signal actuated to indicate the need for winding the clock, and a muffle connected to the visual-signal-actuating mechanism and acting on the striking mechanism of the clock 125 simultaneously with the display of the visual signal and for the same purpose, substantially as described.

6. In a clock winding-alarm, the combination with the clock-movement, of a gear-wheel 130 driven from said movement, a broken ring or bearing adjustably connected to said gear, a lever having an arm bearing on said ring in position to swing through the break thereof,

and connected to a signal device, and means for restoring the lever to normal position, substantially as described.

7. In a clock winding-alarm, a gear actuated from the movement, a broken-ring bearing-piece carried by said gear, a lever having an arm in position to swing through the break in the ring, and a projecting piece on the face of the gear by which the lever is restored to

normal position by the winding of the clock, to all combined substantially as described.

In testimony whereof I affix my signature in presence of two witnesses.

AUGUSTUS G. JACOBS.
